Des. 64,345

UNITED STATES PATENT OFFICE.

JAMES B. DAWSON, OF PORTLAND, OREGON.

DESIGN FOR AN ANDIRON.

Application filed September 21, 1921. Serial No. 502,307. Term of patent 3½ years.

To all whom it may concern:

Be it known that I, JAMES B. DAWSON, a citizen of the United States, residing at Portland, in the county of Multnomah and State of Oregon, have invented a new, original, and ornamental Design for Andirons, of which the following is a specification, reference being had to the accompanying drawing, forming a part thereof.

The figure is a front perspective view of an andiron, showing my new design.

I claim:

The ornamental design for an andiron, as shown.

JAMES B. DAWSON.

Witnesses:

JOHN J. BECKMAN,
FLORA GAMMIE.
